UNITED STATES PATENT OFFICE.

CHARLES A. BALL, OF NEW YORK, N. Y.

STEAM-HEATING SYSTEM

1,198,312

Specification of Letters Patent. Patented Sept. 12, 1916.

Application filed August 13, 1915. Serial No. 45,873.

To all whom it may concern:

Be it known that I, CHARLES A. BALL, a citizen of the United States, residing at New York, in the borough of Manhattan and State of New York, have invented certain new and useful Improvements in Steam-Heating Systems, of which the following is a specification.

My invention relates to steam heating systems, and has for its object to provide for supplying the steam to the radiators or other units of the system by gravity, the steam automatically forcing out of the radiators and piping the air therein.

In carrying out my invention, I provide a sealed system, and admit thereto a heating medium, the same being either live steam under pressure, or exhaust steam, and by means of automatic check and thermostatic relief valves in the return provide for the flow of steam through the system from the top downward, the air in the system, which is of greater specific gravity than the steam, falling to the bottom of the system and passing through the thermostatic element, either by reason of the pressure of live steam forcing it downward, or by reason of the suction induced by an exhaust pump on the return side of the thermostatic element.

In carrying out my invention, the same involves certain details of construction, as will be more definitely pointed out, reference being had to the accompanying drawing, in which:—

Figure 1 is a view in elevation showing a portion of the system, including one radiator and the supply and return to the exhaust pump and condensation pump. Fig. 2 is a detail sectional view of one of the check valves employed with each radiator. Fig. 3 is a similar view of the check valve employed in the condensation return. Fig. 4 is a similar view of one of the thermostatic valves.

In said drawing, the reference numeral 1 denotes the steam supply pipe for the system, having tapped therefrom the pipe 2 which communicates with the radiator 3 at both ends. In that connection with the radiator farthest from the pipe 1 is located a check valve 4, shown in detail in Fig. 2, and which will be hereinafter described. Below the pipe 2 the steam pipe 1 communicates, by means of the pipe 5, with an exhaust pump 6 of any suitable construction, said communication being through a thermostatic valve 7 interposed in the pipe 8,

which communicates between pipes 1 and 5, said thermostatic valve being shown in detail in Fig. 4, and hereinafter described. Below the connection of pipe 5 with the steam pipe 1 is a return pipe connection 9 communicating with the return condensation main 10 of the system, a check valve 11, shown in detail in Fig. 3, being located in said pipe 9, and said condensation return pipe leading to the usual pump 12.

Referring more particularly to Fig. 2, the check valve will be seen to embody a swinging valve member 13, pivoted at 14 in the casing, in such manner as to hang vertically like a pendulum, so as to be normally slightly off its seat when the pressures in the radiator and in the pipe 2 are equalized. By this construction, there is a perfectly free passage from the radiator to the pipe 2, and yet a most efficient check against the slightest back pressure.

In Fig. 3, I have illustrated a preferred form of check valve to be used at 11, the same differing slightly from the check valves 4 in that the swinging valve member 13', pivoted at 14' seats upon a slightly inclined seat 15', and does not have the pendulum-like swing of the valve member 13 of the valve 4. This valve 11, however, is a conventional one and may be purchased in the open market.

In Fig. 4, I have illustrated a preferred form of thermostatic valve 7, the thermostatic element being shown at 16 and there being disposed above said element a ball valve 17, which will open upwardly; but will prevent any return or back pressure.

In operation, the system is sealed effectually against atmosphere, and steam is supplied to the pipe 1 leading downward therein to the radiators or other heating elements. If live steam is used, the elasticity of the same will cause it to advance down the pipe and enter the radiator 3 through the pipe 2, the same building up in the first section of said radiator, which, as shown in section, is cut off at the bottom from the next section thereof, so that the steam will build up in the first section and be supplied therefrom to the successive sections from the top of said first section. As long as the steam pressure is exerted in the radiator 3, there will be a necessary dropping of air in the radiator through the check valve 4 and pipe 2, and the consequent discharge thereof through the thermostatic valve 7 and pipe 5.

to the atmosphere or to the exhaust pump 6. And this discharge of air from the radiator will in no way be retarded by the valve 4, because of its peculiar pendulum-like construction, whereby it is normally free from its seat, and yet ready to respond to the slightest back pressure. Where exhaust steam is used, or steam having heat units but not elasticity, the exhaust pump 6 5 is necessary to draw the entrained air in the radiators and piping from in front of the approaching steam in the pipe 1, but in both cases, the pressure in the radiator being substantially the same as that in the pipe 1, the 10 steam takes the place of the air by gravity, the air dropping to the bottom of the system because of its greater specific gravity, and its place being taken automatically by the steam. It will, of course, be understood 15 that the pump 12 operates to relieve the system of water of condensation, and to return it to the boiler in the usual manner.

I have also shown in Fig. 1, a valve 18 at the top of the radiator 3, which valve is for 20 the purpose of controlling the supply of steam to said radiator. In this connection I prefer to use a valve substantially similar to that disclosed in patent to George W. Hammond, No. 985,526, dated Feb. 28, 1911, 25 though I do not limit myself to such construction. All that is necessary is that the valve 18 shall enable an operator to control the quantity of steam admitted to the radiator, so that if a portion of the steam is 30 cut off, less steam is admitted to the radiator than the latter can condense, which will cause a condensation vacuum in the radiator which will seat the check valve 13 and permit an up-build of condensation, whereby a 35 lesser surface of the radiator will be sub-

jected to contact with the steam, and hence a lowering of the heating effect. It will be understood that the entire system will be controlled in this manner by a single valve like the valve 18, located in the basement of 45 the building, though I contemplate that each radiator shall be so equipped, in order that a separate control may be had at each point of radiation.

Having thus described my invention, what 50 I claim as new and desire to secure by Letters Patent, is:—

1. The method of heating buildings, which consists in controllably supplying steam from a down-flow pipe to the upper part of 55 a radiator unit, and freely returning air and water of condensation from the lower portion of said unit to said pipe, and at the same time preventing the flow of steam in the opposite direction to said radiator unit, 60 whereby water and air of condensation are removed from the unit by gravity.

2. The method of heating buildings, which consists in controllably supplying steam from a down-flow pipe to the upper part of 65 a radiator unit, freely returning air and water of condensation from the lower portion of said unit to said pipe, and at the same time preventing the flow of steam in the opposite direction to said radiator unit, 70 whereby water and air of condensation are removed from the unit by gravity, and finally providing a thermostatic relief for the air.

In testimony whereof I hereunto set my 75 hand this 12th day of August, 1915.

CHARLES A. BALL.
